DESIGN FOR A DESK STAND FOR A HAND TELEPHONE SET

Warren A. Morrison, Maplewood, N. J., and Francis M. Thayer, Jackson Heights, N. Y., as signors to Bell Telephone Laboratories, Incorporated, New York, N. Y., a corporation of New York

Application December 13, 1946, Serial No. 135,466

Term of patent 14 years

(Cl. D26—14)

To all whom it may concern:

Be it known that we, Warren A. Morrison and Francis M. Thayer, citizens of the United States of America, residing at Maplewood, in the county of Essex and State of New Jersey, and at Jackson Heights, in the county of Queens and State of New York, respectively, have invented a new, original, and ornamental Design for a Desk Stand for a Hand Telephone Set, of which the following is a specification, reference being had to the accompanying drawing, forming a part thereof.

Referring to the drawing: The figure of the drawing is a perspective view of a desk stand for a hand telephone set, showing our new design. The dotted line disclosure is for illustrative purposes only.

We claim:

The ornamental design for a desk stand for a hand telephone set, as shown and described.

WARREN A. MARRISON.
